UNITED STATES PATENT OFFICE.

JOHN C. BERTSCH, OF ATLANTA, GEORGIA.

APPARATUS FOR DISTILLING LIQUORS.

SPECIFICATION forming part of Letters Patent No. 714,438, dated November 25, 1902.

Application filed October 23, 1901. Serial No. 79,627. (No model.)

To all whom it may concern:

Be it known that I, JOHN C. BERTSCH, a citizen of the United States, and a resident of Atlanta, in the county of Fulton and State of 5 Georgia, have invented a new and Improved Apparatus for Distilling Liquids, of which the following is a full, clear, and exact description.

This invention relates to an apparatus for 10 distilling liquids, particularly water used in the manufacture of ice. Distilled water or the water of condensation of steam contains a certain quantity of air, and if this water be used for making ice the cakes of ice will 15 have air-bubbles therein. To produce absolutely clear ice, it is necessary to eradicate the air-bubbles from the water by what is known as "reboiling" the water. In order to provide an economical system for this purpose, the water of condensation should be led 20 to the reboiling apparatus at the highest possible temperature; and it is the object of my invention to keep the temperature of this water high, so that it may be economically reboiled. This end I attain by leading the 25 condensed water from the condenser to the reboiling apparatus through means which pass into close proximity to the steam on its way to the condenser, thus heating the condensed 30 water, so that when it enters the reboiler it will be at a high temperature, facilitating boiling it.

This specification is a specific description 35 of two forms of the invention, while the claims are definitions of the actual scope thereof.

Reference is to be had to the accompanying drawings, forming a part of this specification, in which similar characters of reference indicate corresponding parts in all the views.

40 Figure 1 is a diagram of one form of the invention. Fig. 2 is a sectional view of a heater which I prefer to employ, and Fig. 3 is a diagram of a modified form of the invention.

45 Referring to Fig. 1, *a* indicates a pipe leading steam from the source of generation. In the practical application of the invention to an ice-making plant this pipe will lead the exhaust-steam from the engines, pump, and 50 other steam-consuming apparatus of the ice plant. The pipe *a* passes into a heating-drum *b*, and from this drum the steam passes by a

pipe *c* to a condenser *d* of any desired form. This condenser is of such character and capacity that as soon as all of the steam is condensed the condensate is discharged from the condenser. From the condenser *d* a pipe *e* leads back to a coil *f* in the drum *b*, and from this coil passes a pipe *g* to the reboiling apparatus *h*, which also may be of any construction desired. *i* indicates a pipe passing from the bottom of the drum *b* to the reboiling apparatus *h* to carry off from the former the water of condensation therein. Now it is clear that the steam passing into the condenser *d* 65 will be condensed and that the water of condensation running therefrom will pass through the coil *f*. This coil will be heated by the steam in the drum *b*, and the water passing through the pipe *g* to the reboiling apparatus *h* will be at a temperature nearly 70 approaching the boiling-point. Any steam that is condensed in the drum *b* will be led through the pipe *i* to the reboiling apparatus *h*. By this means I heat the water of condensation to a point nearly approaching the boiling-point without involving in any way the expenditure of heat energy additional to that originally required to generate the steam 75 passing through the pipes *a* and *c*.

In order to condense the steam fully and with that rapidity essential to practical success, the temperature of the condenser must be much below that of the boiling-point of water, and hence the condensate will in practice be at a temperature much below this boiling-point. Then by passing this relatively cold water of condensation through the heating-coil *f* the temperature is again raised 85 and reboiling facilitated.

The construction shown in Fig. 2 involves a tubular arm *b'*, passing from the drum *b* and through which the pipe *g* is projected, so that this pipe and the water therein is kept hot until it reaches the reboiling apparatus 95 *h*. This hollow arm *b'* forms a tubular continuation of the drum *b*, as will be clearly understood from the illustration.

Fig. 3 illustrates a construction which involves the use of a pump *k*, by which the water of condensation may be forced into the reboiling apparatus. In Fig. 1 the water flows by gravity from the condenser to the reboiling apparatus; but in Fig. 3 it flows

from the condenser to a tank *l* by way of a pipe *e'*, and from this tank the water is forced through the pipe *e* to the coil *f* in the drum *b* and thence by the tube *g* to the reboiling apparatus *h*.

Having thus described my invention, I claim as new and desire to secure by Letters Patent—

1. An apparatus for distilling water, comprising a condenser, a reboiling device, and means for leading the water of condensation from the condenser to the reboiling device, said means passing into proximity to the steam as the steam passes to the condenser, for the purpose specified.

2. An apparatus for distilling water, comprising a condenser, a means for leading the steam therefrom, said means including a drum, a reboiling device, and a means for conducting the water of condensation from

the condenser to the reboiling device, said means including a coil located in the drum, for the purpose specified.

3. An apparatus for distilling water, comprising a condenser, means for leading the steam thereto, said means including a drum with a hollow arm or extension, a reboiling apparatus, and a means for leading the water of condensation from the condenser to the reboiling apparatus, said means including a coil located within the drum, and a pipe passing from the coil through the hollow arm or extension of the drum.

In testimony whereof I have signed my name to this specification in the presence of two subscribing witnesses.

JOHN C. BERTSCH.
